Filed Feb. 3, 1967, Ser. No. 5,681

Term of patent 7 years

(Cl. D48—23)

FIG. 1

The sides of the light fixture not shown in the drawing are identical in design to the side illustrated in FIGURE 2 and the bottom is devoid of ornamental design.

I claim:

The ornamental design for a surface mounted light fixture, substantially as shown and described.
